UNITED STATES PATENT OFFICE.

EDGAR B. SYMONS, OF HOLLYWOOD, CALIFORNIA, ASSIGNOR TO SYMONS BROTHERS COMPANY, OF MILWAUKEE, WISCONSIN, A CORPORATION OF SOUTH DAKOTA.

DISK CRUSHER.

Application filed November 13, 1925. Serial No. 68,745.

My invention relates to an improvement in disk crushing machines and particularly to an improvement in the guard plates or segments which lie in the plane of discharge of the material crushed, and receive the material centrifugally expelled from between the disks. One object of my invention is to provide such wear plates or segments which shall be simply and easily constructed, assembled and replaced. Another object is to provide such guard plates or members in which the parts receiving the maximum wear are reinforced. Another object is to so shape them as to minimize wear upon them. Other objects will appear from time to time in the course of the specification and claims.

I illustrate my invention more or less diagrammatically in the accompanying drawings wherein:

Figure 1 is a vertical axial section; and Figure 2 is a section on the line 2—2 of Figure 1.

Like parts are illustrated by like symbols throughout the specification and drawings.

A is any suitable crushing member, positioned on a base A¹ and adapted to support a bearing fragmentally shown as A² in Figure 1. Rotating in such a bearing is the hollow shaft B terminating in an outwardly flared cup portion B¹ with an interior spherical surface B² terminating in an outwardly projecting circumferential flange B³.

C is a solid shaft adapted to rotate with in the hollow of the shaft B. C¹ is a spherical head at the end thereof, adapted to conform to the opposed spherical surface B² which is engaged by means of a babbitt bearing member C².

D is a centrally apertured carrying plate having a circumferential rearwardly positioned flange D¹ adapted to be secured to the circumferential flange B³ of the hollow shaft B for example by means of the bolts D², nuts D³ and spacers D⁴.

E and E¹ are opposed concave disks mounted one on the member C¹ and the other on the member D and adapted to define a lenticular crushing space. The means of attaching these disks form no part of the present invention and are not described in detail. The disk E¹ is centrally apertured as at E².

G is a feed spout adapted to feed mate-

rial through the aperture E² to the lenticular crushing space defined by the disks.

Any suitable means not herein shown are provided to rotate the shafts in unison and the material crushed therebetween is centrifugally discharged therefrom.

H, H are guard or material receiving segments aligned in the plane of the disks. They may be secured in position in any suitable manner but I illustrate the perforated lugs H¹ whereby they may be bolted by bolts H² to the surrounding housing and frame structure H³. Each guard section consists of a thickened relatively massive central portion H⁴ and curved or cut away edge or side portions H⁵ H⁶, H⁷ being shortened, to permit the inter-position of the angle iron guard H⁸.

It will be realized that whereas I have illustrated a practical and operative device that nevertheless many changes might be made in the size, shape, number and disposition of parts without departing from the spirit of my invention. I wish, therefore, my description and drawings to be taken as in a broad sense illustrative rather than as limiting me to my specific showing.

The use and operation of my invention are as follows:

The shafts B and C are rotated in unison at a relatively rapid rate. The material to be crushed is fed downwardly along the chute G into the space defined by the opposed disks. The axes of the disks are slightly inclined, the clearance between the disks being therefore greater at the bottom than at the top of the crushing zone as shown in Figure 1. As the pieces of material being crushed drop into the lower portion of the zone and are gripped between the disks they are rotated by the disks, the disks moving in unison, until they reach the upper portion of the crushing zone where the approach of the disks is closer. The result is a crushing operation. As the individual particles are successively crushed to such a size that they can escape from about the peripheries of the disks they are centrifugally ejected. Some of the particles impinge upon the spacer or sleeves D⁴ which protect the securing bolts D² but most of the wear is received by the thickened portion H⁴ of the segments H. The interior conformation of the segments is such that in the first

100
105

place no sharp angles or corners are left and the probability of the material packing in the trough formed by the segments is practically eliminated. This feature is particularly important when moist or somewhat sticky or adhesive material is being crushed.

The prevention of packing is particularly important, since when packing begins it easily fills the entire trough and since, when the trough is filled the wear on the shields ¹⁰ D^4 becomes extreme.

The inward recurvature of the wall members H^5 H^6 prevents rebounding of the particles against the guards or spacers D^4 or ¹⁵ against the edges of the rotating disks. This is particularly important in connection with preventing the material from passing under the edges of the segments, for example between the outer edge of the side H^5 or between the outer edge of the side H^6 and the flange H^7 . The curvature is such that the material, so far as it rebounds, rebounds toward the center of the segment.

In order to permit the discharge of the ²⁵ material, an open space indicated as H^{10} in Figure 2 is left at the bottom of the crushing zone, the material reduced passing downwardly along the various segments and escaping at that point.

³⁰ I claim:

1. In a disk crusher comprising a pair of opposed disks and means for rotating them in unison at such a rate as to expel the reduced material centrifugally from the crushing zone, a receiving member positioned in ³⁵ the plane of discharge of such material, said member comprising a central portion aligned with the peripheries of said disks, and recurved side walls projecting inwardly ⁴⁰ therefrom.

2. In a disk crusher comprising a pair of opposed disks and means for rotating them in unison at such a rate as to expel the reduced material centrifugally from the crushing zone, a receiving member positioned in the plane of discharge of such material, said member comprising a central portion aligned with the peripheries of said disks, and recurved side walls projecting inwardly ⁴⁵ therefrom, the central portion being substantially thicker than the side walls.

3. In a disk crusher comprising a pair of opposed disks and means for rotating them in unison at such a rate as to expel the re-

duced material centrifugally from the crushing zone, a receiving member positioned in the plane of discharge of such material, said member comprising a central portion aligned with the peripheries of said disks, and recurved side walls projecting inwardly ⁵⁵ therefrom, one of said walls terminating about an arc more distant from the center of rotation of the disks than the other.

4. In a disk crusher comprising a pair of opposed disks and means for rotating them ⁶⁰ in unison at such a rate as to expel the reduced material centrifugally from the crushing zone, a receiving member positioned in the plane of discharge of such material, comprising a plurality of segments, each segment ⁶⁵ comprising a central portion aligned with the peripheries of said disks, and recurved side walls projecting inwardly therefrom.

5. For use with a disk crusher comprising ⁷⁰ a pair of opposed disks and means for rotating them in unison at such a rate as to expel the reduced material centrifugally from the crushing zone, a receiving member adapted to be positioned in the plane of discharge of such material, comprising a plurality of segments, each segment comprising a relatively thick central portion aligned with the peripheries of said disks, and relatively thin walls, out of alignment with ⁷⁵ such peripheries, projecting inwardly from the thick central portion.

6. For use with a disk crusher comprising a pair of opposed disks and means for rotating them in unison at such a rate as to expel the reduced material centrifugally from the crushing zone, a receiving member adapted to be positioned in the plane of discharge of such material, comprising a plurality of segments, each segment comprising a relatively thick central portion aligned with the peripheries of said disks, and relatively thin walls, out of alignment with such peripheries, projecting inwardly from the thick central portion, one of said walls ⁹⁰ terminating about an arc more distant from the center of rotation of the disks than the other.

Signed at Hollywood county of Los Angeles and State of California, this 7th ¹⁰⁵ day of November 1925.

EDGAR B. SYMONS.
